ADJUSTABLE LOCK KEEPER

John A. Bohnsack, Waynesboro, Va., assignor to
Hopeman Bros., Inc., New York, N. Y., a corporation of Delaware

Application January 25, 1946, Serial No. 643,274

8 Claims. (Cl. 292—340)

1

This invention relates to keeper devices for door locks and latches and, more particularly, to devices comprising adjustable strike means adapted to be variably positioned to accommodate the position of the lock bolt, one object of the invention being to provide an improved device of the above character having a more simple, practical and efficient construction.

Another object is to provide such a device having adjustable strike means capable of being more accurately adjusted to more precisely correspond with the position of the bolt and hold the bolt and door against rattling.

Another object is to supply a lock keeper having the above advantages and so constructed as to positively resist movement by contact with the bolt and thus maintain its desired position of adjustment.

A further object is to provide such a keeper in a construction comprising relatively few parts, of simple form, adapted to be economically manufactured and conveniently adjusted in use.

To these and other ends the invention resides in certain improvements and combinations of parts, all as will be hereinafter more fully described, the novel features being pointed out in the claims at the end of the specification.

In the drawings:

Fig. 1 is a front view of a lock keeper embodying the present invention;

Fig. 2 is a side elevation, partly broken away and in section, to better illustrate the adjustable strike means;

Fig. 3 is an end elevation;

Fig. 4 is a sectional elevation on the line 4a—4a in Fig. 2;

Fig. 5 is a front view of the strike member detached;

Fig. 6 is an end elevation of the strike member;

Fig. 7 is a front view of the plate forming part of the means for adjusting the strike member, and

Fig. 8 is a sectional plan view on the line 8a—8a in Fig. 2.

The preferred embodiment of the invention herein disclosed, by way of illustration, comprises a main or attaching member having a plane elongated face plate 10, formed with an opening 11 for a locking bolt and also with a latch bolt opening 12 to which the adjustable strike means of the invention is applied in the present instance. Face plate 10 is formed also with a countersunk opening 13 at each end for the reception of screws for securing the same to the

2

jamb of a door frame, as well understood in the art.

Face plate 10 of the attaching member is provided on each side with a rearwardly extending flange 14, as shown, and, opposite the latching bolt opening 12, these flanges have brazed thereto a bottom wall 15 connecting and bracing the flanges and serving as a base to which the strike member is adjustably secured by the means hereinafter described. By this arrangement the attaching member is provided at the latch bolt opening with a rigid box-like frame construction in which the means for adjusting the strike member are supported and housed.

The strike means preferably comprises a plate 16 of angular shape, having a strike lip 17 projecting beyond the plate 10 for engagement with the latch bolt. Lip 17 lies in the plane of the attaching plate 10 and is slidably received in a recess 18 formed by cutting away a portion of the plate 10 opposite its opening 12. Inwardly of the flange 14 the strike plate 16 is turned rearwardly, as at 19, and formed with a channel-shaped portion 20, the base 21 of which rests upon the rear or bottom wall 15 of the attaching member. The base section 21 is formed with a pair of spaced, parallel slots, 22, extending in the direction of movement of the lock to and from striking engagement, transverse to the face of plate 10 and its opening 12, these slots receiving a pair of spaced abutments, preferably in the form of screws 23, with fillister heads, engaged in threaded openings in the bottom wall 15, as shown. The slots 22 provide for adjustment of the strike plate 16 transversely of the face plate 10, to adjust the plate portion 19 for engaging and retaining the bolt in the closed position of the door and the strike member may be clamped in such adjusted position in the attaching member by turning home the screws 23.

The invention comprises means for adjustably positioning the strike member in the attaching member with a high degree of precision, to which end a flat plate 24 is closely and slidably fitted within the channel portion 20 of the strike plate, as shown. Plate 24 is formed with a pair of spaced, parallel slots, 25, extending at an inclination to the directional slots 22 and preferably making a substantial acute angle with such direction, as shown. Slots 25 receive the screws 23, with plate 24 lying under the heads of the screws, so as to be clamped thereby, along with the strike plate, when the screws are turned home.

Plate 24, with the inclined slots 25, serves as

a means for both accurately adjusting the strike plate 16 to suit the position of the latching bolt and for positively locking the strike plate in adjusted position. This is accomplished by inclining slots 25 to the slots 22 of the strike plate 16, at an acute angle of substantial size, so that the direction of the slots 25 is mainly transverse to the direction of the slots 22. An angle of, say, 70°, for example, as indicated in Fig. 7, has been found satisfactory for this purpose. In such an arrangement, with screws 23 unscrewed to release the parts, a small longitudinal adjustment of plate 24 in its channel guide in the strike plate, produces a reduced and slight movement of the strike plate in the direction of its slots 22, so as to effect very slight adjustments and precise positioning of the strike plate.

Furthermore, as a result of the substantial inclination of slots 25 to a direction extending transversely of the face plate 10 and its bolt opening 12, any impacts or pressure of the latching bolt against the strike member and the plate 24 carried thereby, is applied against the screws 23 in a direction which is mainly transverse to the sides of the slots 25 and so nearly perpendicular thereto as to produce no substantial tendency to shift the plate 24 in a longitudinal direction, thereby maintaining the parts in adjusted position.

In operation, to adjust the strike member 16 for close engagement with the latch bolt in the closed position of the door, screws 23 are loosened and plate 24 is engaged by any suitable tool, to shift it longitudinally, in one direction or the other, and thereby effect a reduced shifting of the strike plate 16 toward the desired bolt engaging position. The strike plate may thus be precisely adjusted to proper position for closely engaging the bolt and holding the bolt and the door against rattling. With the parts adjusted to such position and the screws 23 turned home and tightened, the parts are clamped and positively locked in such position against shifting under engagement by the latching bolt.

A lock keeper such as described comprises but few parts, of simple and strong construction and capable of being manufactured at a relatively low cost and the device is adapted to be readily applied to a door frame and conveniently adjusted from time to time to maintain it in efficient working adjustment.

It will thus be seen that the invention accomplishes its objects and while it has been herein disclosed by reference to the details of preferred embodiments, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. An adjustable lock keeper comprising an attaching member formed with a bolt receiving opening, a strike member adjustably mounted on said attaching member, one of said members having an abutment and the other of said members being formed with a slot receiving said abutment with said slot extending in a direction transverse to said opening to provide for adjustment of said strike member relative to said bolt, and a locking part engaging said other member and formed with a slot receiving said abutment, said locking part slot being inclined to said direction and said

part being movable to adjust said strike member in said direction and normally securing said strike member against movement by said bolt.

2. An adjustable lock keeper comprising an attaching member formed with a bolt receiving opening, a strike member adjustably mounted on said attaching member, a screw threadedly engaged in one of said members, the other of said members being formed with a slot receiving said screw with said slot extending in a direction transverse to said opening to provide for adjustment of said strike member relative to said bolt, and a locking part engaging said other member and formed with a slot receiving said screw, said locking part slot being inclined to said direction and said part being movable to adjust said strike member in said direction and being normally clamped in adjusted position by said screw to lock said strike member against movement by said bolt.

3. An adjustable lock keeper comprising an attaching member formed with a bolt receiving opening, a strike member adjustably mounted on said attaching member, a screw threadedly engaged in said attaching member, said strike member being formed with a slot receiving said screw with said slot extending in a direction transverse to said opening to provide for adjustment of said strike member relative to said bolt, and a locking part engaging said strike member and formed with a slot receiving said screw, said locking part slot being inclined to said direction and said part being movable to adjust said strike member in said direction and being normally clamped by said screw to lock said strike member against movement by said bolt.

4. An adjustable lock keeper comprising an attaching plate formed with a bolt receiving opening, a strike plate mounted on said attaching plate at said opening thereof, a plurality of screws threadedly engaged in said attaching plate, said strike plate being formed with a plurality of slots receiving said screws with said slots extending in a direction transverse to said opening to provide for adjustment of said strike plate relative to said bolt, and a locking plate mounted on said strike plate and formed with a plurality of slots receiving said screws, said locking plate slots being inclined to said direction and said locking plate being movable to adjust said strike plate in said direction and being normally clamped by said screws in adjusted position for locking said strike plate against movement by said bolt.

5. An adjustable lock keeper comprising an attaching plate having a portion of box-like construction formed on its face with a bolt receiving opening and with a bottom wall below said opening, a strike plate having a portion extending into said opening and adjustably mounted on said bottom wall, said strike plate being formed with a plurality of slots extending in a direction transverse to said opening for adjusting the position of said strike plate to said bolt, screws extending through said slots and engaged in said bottom wall, and a locking plate slidably mounted on said strike plate and formed with a plurality of slots receiving said screws, said locking plate slots being inclined to said direction and said locking plate being movable on said strike plate to adjust said strike plate in said direction and being normally clamped to said strike plate by said screws to lock said strike plate against movement by said bolt.

6. An adjustable lock keeper comprising an at-

taching member, a strike member adjustably mounted on said attaching member and having a portion of channel shape, a plurality of screws threadedly engaged in said attaching member, said strike member being formed with a plurality of slots receiving said screws with said slots extending in a direction transverse to said opening to provide for adjustment of said strike member relative to said bolt, and a locking part mounted for sliding adjustment in said channel portion of said strike member and formed with a plurality of slots receiving said screws, said locking part slots being inclined to said direction and said part being adjustable in said channel portion to adjust said strike member in said direction and being normally clamped by said screws to lock said strike member against movement by said bolt.

7. An adjustable lock keeper comprising an attaching plate formed with a bolt receiving opening, a strike plate mounted on said attaching plate with a part extending into said opening and having a portion of channel shape, a plurality of screws threadedly engaged in said attaching plate, said strike plate being formed with a plurality of slots receiving said screws with said slots extending in a direction transverse to said opening to provide for adjustment of said strike plate relative to said bolt, and a locking plate mounted for sliding adjustment in said channel portion of said strike plate and formed with a plurality of slots receiving said screws, said locking plate slots being inclined at an acute angle to said direction and said locking plate being adjustable in said channel portion to adjust said strike plate in said direction and being normally clamped by said screws in adjusted position for locking said strike plate against movement by said bolt.

5 8. An adjustable lock keeper comprising an attaching plate having a portion of box-like construction formed on its face with a bolt receiving opening and with a bottom wall below said opening, a strike plate having a lip part and a part extending into said opening and having a portion of channel shape mounted on said bottom wall, said channel portion being formed with a plurality of slots extending in a direction transverse to said opening for adjusting the position of said strike plate to said bolt, screws extending through said slots and engaged in said bottom wall, and a locking plate mounted for sliding adjustment in said channel portion and formed with a plurality of slots receiving said screws, said locking plate slots being inclined at an acute angle to said direction and said locking plate being adjustable in said channel portion to adjust said strike plate in said direction and being normally clamped in adjusted position by said screws to lock said strike plate against movement by said bolt.
